JOSEPH JOHN SMITH, JR., OF BENTON HARBOR, MICHIGAN.

VALVE FOR AIR-COOLED SPARK-PLUGS.

1,363,623.

Specification of Letters Patent. Patented Dec. 28, 1920.

Application filed April 2, 1919. Serial No. 286,841.

To all whom it may concern:

Be it known that I, JOSEPH JOHN SMITH, Jr., a citizen of the United States, residing at Benton Harbor, in the county of Berrien 5 and State of Michigan, have invented certain new and useful Improvements in Valves for Air-Cooled Spark-Plugs, of which the following is a specification.

My invention relates to improvements in 10 valves for air cooled spark plugs, and it consists in the combinations, constructions and arrangements herein described and claimed.

An object of my invention is to provide 15 a valve which will act automatically on the intake stroke of the piston of the engine to which the spark plug is applied to permit a stream of cold air to play on the spark plug tips, thereby tending to free the latter of 20 any carbon accumulation, and keeping the spark plug cool.

A further object of my invention is to provide a device of the type described in 25 which the valve requires only a very slight movement to permit the required amount of air to enter.

Other objects and advantages will appear 30 in the following specification, and the novel features of the invention will be particularly pointed out in the appended claims.

My invention is illustrated in the accompanying drawings, forming part of this application, in which—

Figure 1 is a vertical sectional view 35 through a spark plug embodying my invention;

Fig. 2 is a sectional view through a portion of a modified form;

Fig. 3 is a sectional view through a portion 40 of another modified form;

Fig. 4 is an enlarged section along the line 4—4 of Fig. 3;

Fig. 5 is a sectional view of a portion of 45 another modified form; and

Fig. 6 is an enlarged section along the line 6—6 of Fig. 5.

Referring now to Fig. 1, I have shown 50 therein an insulating core 1 having a central passage in which is disposed a hollow conductor 2 provided with a sparking tip 3 which may be made of any suitable metal. The tube or conductor 2 is threaded at 4 to engage the threaded opening in the bottom 5 of a metal cylinder 6, which is hollow, 55 and whose upper open end is threaded at 7 to engage a threaded opening in the lower

end of a cap 8. The latter has at its top a recess 9 and a central passage 10 arranged to communicate with the interior of the cylinder 6. A groove 11 is provided for the 60 terminal clip. A valve 12 fits snugly on the interior of the cylinder 6 and is provided with a recess 13 arranged to receive the upper end of the conductor 2. The upper end of the valve 13 shown in Fig. 1 is of a 65 conical shape to engage a conical valve seat 14 in the cap 8. A passage 15 extends from the recess 13 and terminates at the conical end of the valve in the manner shown. A gasket 16 is provided between the end of the 70 cylinder 6 and the insulating core 1. The core with its connections as described above, may be used with any suitable shell.

From the foregoing description of the 75 various parts of the device, the operation thereof may be readily understood. On the intake stroke of the engine the valve 12 will be moved against the tension of the spring 17 away from its seat 14, thereby permitting air to pass through the passage 10, 80 the passage 15, the recess 13, and through the interior of the conductor to the terminal 3. The cap 8 by reason of the recess 9, serves as a priming cup.

In Fig. 2 I have shown a modified form 85 in which the block 18 is provided with a cylindrical recess 19 having therein a valve 20 which is provided with a passage 21 therethrough, and may be provided with a passage 22 shown in dotted lines. The cap 90 23 screws into the upper end of the recess or bore 19. A second cylindrical recess 24 is normally closed by a screw plug 25. A ball valve 26 fits on a semi-spherical seat 27. A passage 28 connects the recess 19 with the 95 recess 24, while a passage 29 connects the recess 24 with the interior of the hollow conductor 2^a.

In this form of the device, on the intake stroke of the engine, the ball valve 26 is 100 raised from its seat, while the valve 20 is moved downwardly against the tension of the spring 20^a, and air passes through the valve 20, the recess 19, passage 28, recess 24, and by passage 29 to the interior of the 105 conductor 2^a. The action of the ball valve 26 is facilitated by providing by-passes 30 in the wall on each side of the ball valve.

In Fig. 3, the cap and cylinder are formed 110 in one piece as shown at 31, the lower portion of the cylinder being screwed to a socket 32 which is in turn connected with the hol-

low conductor 2^b. In this form of the device the valve 33 is cylindrical as shown in Fig. 4, and has radial openings 34 communicating with a circumferential groove 35, the latter being in communication with bypasses 36 in the wall of the member 31, so that when the valve is moved away from its seat, air will pass down the by-passes 36 through the groove 35, and the openings 34, and thence through the hollow conductor 2^b.

In Fig. 5, the valve 37 is cylindrical, and is provided with longitudinal grooves 38, and a transverse groove 39, which communicates by means of an opening 40 with the interior of the hollow conductor 2^c. The valve when leaving its seat in the member 41, permits air to pass downwardly through the passages 38, 39, and 40 into the interior 20 of the hollow conductor 2^c.

I claim:

1. In a valve construction for air cooled spark plugs, an insulating core, a hollow conductor carried thereby, a cylinder carried by the core, a cylindrical valve disposed in said cylinder and having a conical end, a conical-shaped valve seat carried by the cylinder, and a passage in the body of the valve for establishing communication between one end of said hollow conductor and the space between the conical end of the valve and its valve seat when the valve has left its seat.

2. In a valve construction for air cooled spark plugs, an insulating core, a hollow conductor carried thereby, a cylinder carried by the core, a cylindrical valve disposed

in said cylinder and having a conical end, a conical-shaped valve seat carried by the cylinder, a passage in the body of the valve 40 for establishing communication between one end of said hollow conductor and the space between the conical end of the valve and its valve seat when the valve has left its seat, and a spring disposed between the cylinder 45 for normally retaining the valve on its seat.

3. In a valve construction for air cooled spark plugs, an insulating core, a hollow conductor carried thereby, a cylinder carried by the core, a cylindrical valve disposed 50 in said cylinder and having a conical end, a conical-shaped valve seat carried by the cylinder, said valve having a recess at the end opposite the conical-shaped end for receiving the end of the hollow conductor to 55 guide the valve in its movement, and a spring disposed between the cylinder and arranged to bear on the end of the valve having the recess.

4. In a valve construction for air cooled 60 spark plugs, an insulating core, a hollow conductor carried thereby, a cylinder carried by the core, a cylindrical valve disposed in said cylinder and having a conical end, a conical-shaped valve seat carried by the 65 cylinder, said valve having a recess at the end opposite the conical-shaped end for receiving the end of the hollow conductor to guide the valve in its movement, a spring disposed between the cylinder and arranged 70 to bear on the end of the valve having the recess, and a passage extending from the recess to the conical end of the valve.

JOSEPH JOHN SMITH, JR.
